UNITED STATES PATENT OFFICE.

EZRA S. BUCKNAM, OF PHILADELPHIA, PENNSYLVANIA, ASSIGNOR TO
JOHN A. BRILL, OF PHILADELPHIA, PENNSYLVANIA.

DOOR STOP AND CATCH FOR VESTIBULE OR OTHER DOORS.

SPECIFICATION forming part of Letters Patent No. 784,381, dated March 7, 1905.

Application filed May 16, 1904. Serial No. 208,175.

To all whom it may concern:

Be it known that I, EZRA S. BUCKNAM, a citizen of the United States, and a resident of the city and county of Philadelphia and State of Pennsylvania, have invented a new and useful Improvement in Door Stops and Catches for Vestibule or other Doors, of which the following is a specification.

The object of my invention is to provide an article of this class which will securely and firmly hold a door which may swing against it and hold the door open. This object is accomplished by my invention, certain embodiments of which are hereinafter described.

For a more particular description of the same, reference is to be had to the accompanying drawings, forming a part hereof, in which—

Figure 1 is a side elevation of my improved catch and its coöperating parts. Fig. 2 is a plan view of the catch and stop. Fig. 3 is an end elevation of the same. Fig. 4 is a sectional view taken on the line 4-4 of Fig. 2 looking in the direction of the arrows. Fig. 5 is an elevation of a modified form, a part being shown in section.

Throughout the various views similar reference characters designate similar parts.

While my improved stop and catch is adapted for use on all kinds of doors and wherever desired, it is more particularly adapted for use on the folding doors of vestibule street-cars, as will more fully hereinafter appear, and may be attached to any convenient part of the car near the edges of the door when the door is in its open position, although it is preferable to place this stop and catch in the floor, where it will be entirely out of the way and conveniently located.

The stop and catch 1 comprises a plate 2 with screw-holes 3 and a longitudinal rectangular slot 4, with upwardly-extending ears or lugs 5 adjacent to one end of the slot. The lower surface of the plate, which is the surface opposite the one on which the lugs are placed, is provided with a small flange 6, which surrounds the slot 4. When in use, this plate is countersunk into the surface or platform to which it is attached and held with its upper

face flush with the surface or plate, as is apparent in Fig. 1, and is held in position by screws 7. A fulcrum or pivot pin 8 unites the ears 5, and pivoted thereon is the bent lever 9. This lever is provided with flanges 10 to make it fit snugly between the ears 5 and below the pivot 8 is bent at right angles, so as to rest in the slot 4 and to have a free movement therein. Above the pivot-pin 8 the lever 9 is enlarged and extended rearwardly and is bored out to form a chamber 11, which is partially closed by an internal collar 12, the outer surface of which is flared to receive a screw-head 13 of a screw 14. The other end of the screw 14 is screwed into a buffer 15, which is so shaped as to snugly fit the bore of the chamber 11 and yet be free to slide therein. A coil-spring 16 rests between the collar 12 and buffer 15 and encircles the screw 14 and normally holds the screw-head 13 snugly against the collar 12. If desired, the tension of this spring 16 may be varied by turning the screw 14 in the buffer 15; but as the exact adjustment of this spring is not very important it is probable that such adjustment will be unnecessary. The part of the lever 9 which rests in the slot 4 is preferably extended upwardly at the end farthest removed from the pivot-pin 8 and slightly undercut at 17 to form a shoulder for a purpose which will appear below, and a head 18, 80 which is spread laterally beyond the walls of the slot 4 and slightly over the plate 2. The precise shape of the head 18 is immaterial, but is preferably as shown.

When the catch and stop is secured to the floor or platform of a car, the platform 19 is slotted at 20, so as not to interfere with the movement of the bent lever 9, and the vestibule-doors 21 and 22 are hinged in the usual manner—that is, one edge of the door 21 is hinged to the door 22 and the other edge is hinged to a post or the car-body, as may be convenient—and when the doors are open a plate 23 on the door 21 comes in contact with the buffer 15, thereby swinging the head 18 upwardly until its undercut edge 17 engages a nose 24, secured to the lower edge of the door 22. The parts are so adjusted that the

spring 16 is placed under slight tension, so that the nose 24 and head 18 are kept in close contact by the pressure of the spring exerted through the buffer 15 and the plate 23.

- 5 When my improved stop and catch is placed on the platform, as above described, and the door is closed, so that the stop and catch is not in use, the weight of the head 18 and the parts adjacent thereto is sufficient to cause
- 10 the extended edges of this head to rest on the plate 2 and hold the buffer 15 in the path of the plate 23 when the door is open, so that no further mechanism or change is required to render the stop and catch operative; but when
- 15 the catch and fastener is inverted by being placed in the ceiling or partially inverted by being placed on its side certain modifications are essential, because if they were omitted the weight of the head 18 and the parts adjacent thereto would be so great that they would be in the path of the plate 23 and not the buffer 15, so that my improved device would be inoperative without the changes above referred to. These changes would be apparent from
- 20 Fig. 5, in which the structure is modified. The head 18^a is beveled on the outer face 18^b and slightly extended longitudinally of the lever 9^a, for reasons which will be given below. In this modification the plate 2 is done away
- 25 with and in lieu thereof the bracket 30 is substituted, which bracket is adapted to be secured to a vertical instead of a horizontal surface and is provided with upwardly and outwardly extending parallel ears 31, which are
- 30 in planes perpendicular to the plane of the base 32 of the bracket. The bent lever 9^a is fulcrumed on a pin 8^a, which unites the ears 31, and the said bent lever is placed between the ears, and its rear extremity 26 impinges
- 35 against a stop 25, which stop is a lug that depends from a web 27, which unites the ears 31, but does not extend far enough to interfere with the movement of the bent lever 9^a. The height of this stop 25 is such that when
- 40 it is impinged against by the end 26 of the lever 9^a the head 18^a is held so that the beveled face would be in the path of the plate 23^a at the top of the door 21, so that when the door

is opened in the unusual manner the head 18^a is raised and the door passes under the same 50 and the plate 23^a engages the buffer 15^a, thereby causing the undercut edge 17^a to engage the nose 24^a, when the doors 21 and 22 will be held in precisely the manner described above. In either case the doors may be released by 55 simply causing the head to disengage the nose against the action of the coil-spring, when the doors may be closed, as is apparent.

For convenience it is preferable to make the lever 9 hollow, as shown in Fig. 4; but this 60 is not necessary, as it may be made solid, if desired, although such a structure would involve a considerable waste of material.

Various other modifications may be made as to size and proportion of parts and in other 65 ways, all of which come within the scope of my invention and which are covered by the annexed claims.

Having thus described my invention, what I claim is—

1. In a door stop and catch or similar device, a slotted plate with ears adjacent to said slot, a bent lever fulcrumed between said ears, and having a portion extending between the walls of the slot, a buffer secured near one end of 75 said lever, and a catch at the other end of said lever.

2. In a door stop and catch or similar device, a slotted plate with ears projecting near the slot, a bent lever fulcrumed between said ears, 80 and having a portion resting between the walls of the slot and the catch at one end of said lever, comprising an enlarged head, a portion of which extends beyond the slot and over the plate and a buffer at the other end of said lever. 85

3. In a door stop and catch, a slotted plate, a bent lever pivoted in the slot in said plate, a spring-actuated buffer at one end of said lever, and a catch adapted to engage a door at 90 its other end.

Signed this 13th day of May, 1904.

EZRA S. BUCKNAM.
